UNITED STATES PATENT OFFICE.

AUGUST E. NEFF, OF CHICAGO, ILLINOIS, ASSIGNOR TO PHOENIX TRIMMING COMPANY, OF CHICAGO, ILLINOIS, A CORPORATION OF ILLINOIS.

FRINGE FOR RUGS AND THE LIKE AND METHOD OF MAKING THE SAME.

Application filed April 21, 1922. Serial No. 555,874.

To all whom it may concern:

Be it known that I, AUGUST E. NEFF, a citizen of the United States, residing at Chicago, in the county of Cook and State of

5 Illinois, have invented certain new and useful Improvements in Fringe for Rugs and the like and Methods of Making the Same.

The invention will be described as embodied in an ornamental fringe or edging 10 for rugs curtains, upholstery and the like.

The primary object of the invention is to produce an article of manufacture such as stated comprising a tasselled fringe or edging having a sufficiently firm structure to 15 adapt the same as an ornamental finishing for rugs and the like.

It is a further object of the invention to produce a fringe or edging of the character stated at a greatly reduced cost and one that 20 will be superior in appearance and adaptability to the uses to which such materials are usually put.

Other objects of the invention will appear 25 from the following description which is directed to the preferred embodiment of the invention, reference being had to the accompanying drawings forming a part thereof, the novel features being more particularly set forth in the appended claims.

30 The invention will now be described in detail, reference being had to the accompanying drawings forming a part of the specification in which Fig. 1 is a schematic view showing the course of the warp and filler strands in the manufacture of a tasselled fringe having a single binder course uniting the tassels, as shown in Fig. 2.

Fig. 3 is a schematic view showing the 40 course of the warp and filler strands in the manufacture of a tasselled fringe having two binder courses uniting the tassels, as shown in Fig. 4.

Like reference characters designate like parts throughout the drawings.

45 Reference character A (Figs. 1 and 2) designates generally that portion of the fringe which will for the sake of clarity be termed the "mat" which may be woven in any suitable weave and consists of any de-

50 sired number of warp strands to form the desired width of the "mat" and preferably a plurality of filler strands in each shot through the sheds of the warp strands, the

number of filler strands included in each shot depending upon the design of the fringe 55 to be attained in the finished product.

As illustrated in Fig. 1 of the drawings each shot of the filler embraces four filler strands designated by reference characters

10, 11, 12 and 13. After the filler strands 60 are shot through the sheds of the warp strands in one direction the heddles or harness of the loom shift in the ordinary manner forming a new shed, and the filler strands are shot therethrough in the opposite direction a predetermined distance 65 beyond one edge of the "mat" where they are cut by the loom knife or may be subsequently cut forming the tassels of the fringe. At a

point intermediate the edge of the "mat" 70 and the free ends of the filler strands, the filler strands are bound by a binding course

consisting of warp strands 17 and designated generally by the reference character

B. The tassels designated generally by reference character C are thus made up of the 75 filler strands laid in multiples of four strands, for example, as shown in the drawings.

To form the size of the tassels, the weft strands are at intervals folded backwardly or toward the "mat" and passed

80 through the sheds formed in the strands of warp in the binder course B, and by suitably shifting the heddles or harness of the loom this interval weaving of the weft multiple strands may assume the form shown

85 at D, or any desired number of loops or sinuses which will determine the spacing between the tassels as well as the tassels' size. It will be readily seen by reference to

90 Fig. 2 that the looping of the filler strands, as designated by the reference character D, through the binder course B forms spaces

15 between the tassels C, giving the fringe a highly ornamental effect. After the

95 fringe has been formed as described, on the loom, it is placed on a sewing machine and one or more rows of stitching run through

100 the binder course B, as designated by reference character 16, to prevent the shifting of the filler strands with relation to the binder course B.

In Figs. 3 and 4 is shown a modified and 105 more ornate form of fringe having a mat designated generally by the reference character E, and two binder courses designated

generally by the reference characters F and G, the mat E having warp strands 17 and filler strands 18 with warp strands 19 for forming a second or supplemental binder 5 course F, and warp strands 20 for forming binder course G.

In the modified form of the invention, as shown in Figs. 3 and 4 the filler strands are caught and bound in groups, designated as 10 H and O by binder courses F and G, respectively, and in this form of the invention each shot of filler comprises preferably although not necessarily three strands 18, which are shot through binder F and looped 15 backwardly toward mat E, and the heddles of the loom shifted, forming a new shed and the filler strands shot therethrough in the opposite direction, when the heddles are again shifted and the looped filler strands 20 shot through binder G becoming a part of the tassels, thereby forming spaces 21, between the groups H. Each of the groups H are divided into two portions of an equal number of filler strands and the contiguous 25 portions of contiguous groups bound by binder course G, thus forming tassels L. Three of the filler strands 18 are looped upon themselves in double loops between tassels L and bound by the shifting of the heddles 30 with warp strands 20, and then carried backwardly through binder course F and mat E, thus forming the spacing loops D in binder course G, and so spacing the tassels L apart.

In the form of the fringe having the double 35 rows of binder courses as described in connection with the disclosure in Figs. 3 and 4, the tassel and tassel loops are also firmly united by stitching with one or more rows 40 of stitching through binder courses F and G and parallel with the wrap strands comprising the same, just as shown in the drawing and as I have described the stitching through binder course B of Figs. 1 and 2.

45 I have found this firm uniting of the tassel strands through warp binder courses by stitching, of the greatest importance when the fringe is used as a finishing for rugs. The stitching gives a surprising firmness 50 to the fringe, making it easier to attach to the end of a rug as an ornate finishing or trimming means; makes the fringe lay better on the floor; prevents distortion by the pulling or kinking of the tassel 55 strands through the binder courses when subjected to floor use; and finally greatly enhances the life of the fringe on a rug because, when the binder strands on an unsewn fringe is worn through, the tassel 60 strands loosen and roughen up, which renders it unsightly and practically unserviceable, while if stitched as described, the abrading or destruction of the binder course at any given point will not release the 65 strands of the tassels, which will neverthe-

less continue to be firmly held in normal position by the stitching.

In order that the invention might be understood the details of the preferred embodiment have been shown and particularly 70 described, but it is not desired to be limited to the mere details of the invention, for it will be apparent that persons skilled in the art may resort to various modifications without departing from the purpose and 75 spirit of the invention.

I claim:

1. A fabric having a mat formed of warp strands and filler strands, the filler strands 80 extending beyond one edge of the mat and being bound together by a binder course intermediate the edge of the mat and the ends of the filler strands, and stitching uniting the filler strands and the binder course.

2. A fabric having a mat formed of warp 85 strands and filler strands, the filler strands extending beyond one edge of the mat and being bound together intermediate the edges of the mat and the ends of the strands by warp strands, forming tassels spaced apart 90 and stitching extending transversely of the tassels through the binding warp strands.

3. A fabric having a mat formed of warp 95 strands and filler strands, the filler strands extending beyond one edge of the mat and being bound together intermediate the edge 100 of the mat and the end of the strands by warp strands forming tassels, the tassels being spaced apart by an intervening portion of the fabric, and stitching extending transversely of the tassels through the binding warp strands.

4. A fabric having a mat formed of warp 105 strands and filler strands, the filler strands extending beyond one edge of the mat and being bound together intermediate the edge of the mat and the ends of the strands forming tassels, the tassels being spaced apart by the looping of a portion of the 110 filler strands in the weave therebetween, and stitching extending transversely of the tassels and looped portions of the filler strands where bound together.

5. A fabric comprising a mat and a binder 115 course formed of warp strands and filler strands, the binder course being spaced from the mat, the filler strands extending through and beyond one edge of the mat and through the binder course and being bound together intermediate the edge of the mat and the 120 ends of the strands forming tassels, the tassels being spaced apart by a portion of the fabric woven therebetween, and stitching through the binder course uniting the spacing means and the tassels.

6. The method of forming a fabric by interweaving filler strands for a portion of their length with warp strands thereby 125 forming a mat with certain of the filler strands extending beyond one edge of the 130

mat and at the same time interweaving a predetermined number of the filler strands with a course of warp strands separated from the body of the mat intermediate the 5 edge of the mat and the ends of the filler strands, and then stitching through the last said warp strands along a line parallel therewith for the purpose of securing the filler strands to the binder course intermediate 10 the edge of the mat and the ends of said filler strands.

7. The method of forming a fabric comprising a mat and a plurality of binder courses by interweaving the warp strands 15 and the filler strands to form the mat and the binder courses, there being a plurality of the binder courses spaced from the mat and apart from each other, the said binder courses serving to hold the filler strands 20 looped in opposite directions through the binder courses spaced from the mat, the said looped filler strands and the spaced binder

courses being secured to the tassels by stitching through the binder courses.

8. A fabric comprising a woven mat of 25 warp strands and weft strands, the weft strands of the fabric extending on one side of the mat to form a fringe, there being certain of said weft strands looped and interwoven with two separated groups of warp 30 strands spaced apart from the mat body to form binder courses for securing and holding the weft strands in position to form tassels, and rows of stitching for securing the tassels and binder courses firmly together paralleling the aforesaid warp strands of the spaced binder courses and intersecting the looped portions of the weft strands in the binder courses.

In testimony whereof I have signed my 40 name to this specification on this 11th day of April A. D. 1922.

AUGUST E. NEFF.
